Rubbermaid Sales Corp., Wooster, Ohio

Filed Nov. 1, 1972, Ser. No. 302,642

Term of patent 14 years

Int. Cl. D6—11

U.S. Cl. D6—210

FIG. 2

FIG. 1 is a top plan view of a bathtub mat showing my new design. The solid line flower designs are continuous and the circumference of the broken line circles represent the outer circumferences of additional flowers such as shown in solid lines.

FIG. 2 is a side elevation thereof.

FIG. 3 is an enlarged partial sectional view on line 3-3 of FIG. 1.

FIG. 4 is an enlarged partial plan view thereof.

I claim:

The ornamental design for a bathtub mat, as shown and described.
